ANALYTICAL BALANCE

Werner Ruefenacht, Salt Lake City, Utah

Application December 29, 1952, Serial No. 22,900

Term of patent 14 years

(Cl. D52—10)

To all whom it may concern:

Be it known that I, Werner Ruefenacht, a citizen of the United States and a resident of Salt Lake City, county of Salt Lake, and State of Utah, have invented a new, original, and ornamental Design for an Analytical Balance, of which the following is a specification, reference being had to the accompanying drawing, forming part hereof.

Fig. 1 is a front elevational view with the cover closed, of an analytical balance showing my new design;

Fig. 2, a top plan view;

Fig. 3, a side elevational view;

Fig. 4, the same as Fig. 3 with the cover in the open position; and

Fig. 5, a view in perspective.

I claim:

The ornamental design for an analytical balance, substantially as shown.
